UNITED STATES PATENT OFFICE.

JOHN G. MORAN, OF BROOKLYN, NEW YORK, ASSIGNOR TO A. KIMBALL COMPANY, OF NEW YORK, N. Y., A CORPORATION OF NEW YORK.

MARKING TICKET.

Application filed October 11, 1924. Serial No. 743,023.

This invention relates to marking tickets such as are commonly employed for attachment to articles of clothing to indicate size, price, etc., and for other purposes.

5 Such marking tickets are commonly secured in place by prong fasteners made of wire secured to the body of the ticket. It is important, however, in the use of these marking tickets upon silk and other fabrics 10 and articles of a delicate or expensive nature, that the pin or prong fasteners employed shall not be of a character to catch the fine fibres or of a character to cut the fine threads forming the fabric. The ordinary household pin is readily obtainable 15 in large quantities at small expense and presents a smoothly finished point which will not catch the fibres or cut the threads when passed through silk and other fine and delicate materials.

The object of the present invention is to provide a marking ticket adaptable for attachment to the article to be marked by means of such a pin; and the object of the 25 invention more particularly is to provide a construction of ticket which shall protect or cover the head of the pin at both faces of the ticket. The head of the household pin is usually very much larger than the shank, 30 and if left uncovered or unprotected, it may catch upon some portion of the article, or upon other articles, or in various ways be caught so as to be withdrawn from the ticket and thus cause the separation of the ticket 35 from the goods. In the present invention, the construction of the ticket is so arranged that the head of the pin is covered at both faces of the ticket by the material of the ticket.

40 These and other objects and features of the invention will be apparent from the accompanying description and drawings, and will be particularly pointed out in the claims.

In the drawings:

45 Fig. 1 is a rear view of a portion of a piece of fabric with a marking ticket embodying the preferred form of the present invention attached thereto.

Fig. 2 is a view similar to Fig. 1 with the 50 covering flap of the ticket open.

Fig. 3 is a front view of the construction shown in Fig. 1.

Fig. 4 is a view in cross section taken on the line 4—4 of Fig. 1.

55 The body of the ticket may be made of

any suitable material, such as cardboard, which is employed in the manufacture of marking tickets. So also the size of the ticket and its particular shape will depend upon the purposes for which it is to be used. 60

Whatever its material or size, the marking ticket of this invention essentially comprises two connected, foldable main flaps. The main flap 1 is preferably of rectangular shape and connected at the line of fold 2 65 to the second similar main flap 3.

The first main flap 1 is provided with a transverse slot 4, and between the free end 5 of this flap and the said slot 4 there are three, preferably transversely, aligned apertures, 6, 7 and 8. Two of these apertures, 6 and 7, are comparatively widely separated and are for the purpose of allowing the pin to pass back and through the ticket and the material, while the third aperture 8 forms 70 a pocket for the head of the pin.

The second main flap 3 is provided near its free end with two apertures. One of these, as 9, is juxtaposed to the aperture 6 of the first main flap, and the other 10 to the aperture 7, or in other words the two apertures 9 and 10 are juxtaposed one to the central aperture of the first main flap, and the other to one of the end apertures of the first main flap when the two flaps are in 75 their folded position.

A covering flap 11 is connected with the free end 5 of the first main flap 1 and is of a size such that it may be folded over the three apertures, 6, 7 and 8, and then passed 80 through the slot 4 so as to extend between the flaps 1 and 3.

The ticket presents on the main flap 1 below the transverse slot 4 a large area upon which suitable indicia may be placed and 85 on the main flap 3, below the apertures 9 and 10, an even larger space for suitable indicia.

The manner of use may now be apparent. The flaps 1 and 3 of the ticket are folded 100 together, and the ticket is then slipped over an edge 12 of the article to be marked. An ordinary household pin 13 is then passed through the juxtaposed apertures 7 and 10 of the ticket and the interposed material, 105 and then back through the juxtaposed apertures 9 and 6 and the interposed material, and the head is positioned in the aperture 8 of the flap 1. The covering flap is now tucked in place through the transverse slot 110

4. The head of the pin lying in the aperture 8 is now covered on one side by the flap 11 and at the other side by the flap 3. Thus the pin is thoroughly protected and
5 there is no danger of its being caught or drawn out and thus the ticket becoming separated from the article.

Having thus described the invention, what is claimed as new and desired to be secured
10 by Letters Patent, is:

1. A marking ticket for attachment to goods by means of an ordinary headed pin comprising two connected foldable main flaps adapted to receive between them the
15 article to be marked; the first main flap having a transverse slot and, between its free end and said slot, three aligned apertures; the second main flap having two
20 apertures juxtaposed to the central and one end aperture of the first main flap when the flaps are in folded position; and a covering flap connected with the free end of the first main flap, foldable thereupon over the three apertures and shaped to enable it
25 to be passed through said slot and extend between the main flaps, whereby, when the ticket is folded upon the interposed goods and a pin is passed through the juxtaposed apertures, the head of the pin will lie

in the third aperture in the first main flap 30 and will be covered at one side by the second main flap and at the other side by the covering flap.

2. A marking ticket for attachment to goods by means of an ordinary headed pin 35 comprising two connected foldable main flaps adapted to receive between them the article to be marked; the first main flap having a transverse slot and between its free end and said slot, a pin-head receiving aperture; a covering flap connected to the free end of the first main flap, foldable thereupon and shaped to enable it to be passed through said slot and extend between the main flaps; and both main flaps being 40 further apertured to enable the pin, when the ticket is folded upon the interposed goods, to be passed from the outer side of the first main flap through and back through 45 the entire ticket and interposed goods and to allow the head of the pin to lie in the pin-head receiving aperture covered at one side by the first main flap and at the other side by the covering flap.

In testimony whereof, I have signed my 55 name to this specification.

JOHN G. MORAN.
